ING ENGINE COMPANY, OF ROCHESTER, NEW YORK, A CORPORATION OF NEW
YORK.

DEEP-WELL PUMP.

1,425,673.

Specification of Letters Patent. Patented Aug. 15, 1922.

Application filed July 25, 1921. Serial No. 487,387.

To all whom it may concern:

Be it known that I, WILLIAM A. MINOR, a citizen of the United States, and resident of Rochester, in the county of Monroe and State of New York, have invented certain new and useful Improvements in Deep-Well Pumps, of which the following is a specification.

The present invention relates to deep well pumps and more particularly to the type employing an upper and a lower bucket working in opposite directions. An object of this invention is to provide a construction in which the passageway through the pistons or buckets is increased to a maximum, while at the same time giving effective valve seats which have no tendency to leak. Another object of the invention is to effectively support the pistons or buckets from points about the valves so that only one valve seat is required for each valve and the area of the passageway through the bucket may be increased. Still another object of the invention is to provide a construction in which the upper valve operates directly about the rod of the lower piston and has a packing relation with said rod so that leakage between the rod and the valve is nil. A still further object of the invention is to provide for packing the pump against surge between the rod carrying the lower bucket or piston and the hollow rod carrying the upper bucket or piston.

To these and other ends, the invention consists of certain parts and combinations of parts, all of which will be hereinafter described, the novel features being pointed out in the appended claims.

In the drawings:—

40 Fig. 1 is a central vertical section through a portion of a deep well pump constructed in accordance with this invention, the operating mechanism not being shown and being of any approved form;

45 Fig. 2 is a section on the line 2—2, Fig. 1;
Fig. 3 is a section on the line 3—3, Fig. 1; and

Fig. 4 is an enlarged vertical section through the upper valve.

50 Referring more particularly to the drawings, 1 indicates the barrel of the pump, 2 the upper bucket or piston, and 3 the lower bucket or piston. The lower bucket comprises, preferably, a cylindrical portion having a central passageway 4 and surrounded

by packing which, in this instance, comprises cup members 5 held on the bucket 3 by a clamping member 6 which is secured in place by nuts 7 on bolts 8, there being provided between the packing cups 5, spacing rings 9. The lower bucket has at the top of its passageway, a seat 10 which may be of bevelled or chamfered form with which a valve member 11 cooperates. This valve member has projections 12 depending therefrom, in this instance, four in number, two of said projections opposite each other being bevelled at 13. The flow of the water through the piston acting on this inclined or bevel face 13 tends to produce a rotary motion of the valve and thus makes it self-grinding and brings new parts of the seat in contact with the valve on each stroke, this being particularly valuable when the liquid being pumped contains sand, grit or other foreign substances. The piston or cylinder is operated by a stem 14 which, in this instance, has screw threaded engagement at 15 with a cage 16, this cage having a ring 17 at its lower part internally threaded and engaging external threads on the piston or cylinder 3 about the valve 11. It is apparent that by this arrangement the rod 14 connects with the lower piston or bucket in such a manner that it does not restrict the passageway through the bucket or piston. At the same time only one seat is required for the valve and the now most commonly employed two-seat valve arrangement is eliminated thus also eliminating the leakage due to the uneven wearing of the two seats. While the valve will close by the pressure of water above it, this closing may be assisted by a spring 18 of helical formation seated at its lower end against the valve 11 and its upper end against the cage about 85 an annular projection 19 on the interior of said cage.

The upper bucket or piston like the lower bucket has packing rings 5 about it held by a clamping collar or ring 6 through bolts 8 and nuts 7, the packing rings 5 also being spaced by spacing rings 9. The piston has a passageway therethrough in which a spider 20 is arranged and through this spider 100 the piston rod 14 of the lower piston operates. At the upper end of the passageway is a seat 10^a with which a valve member 11^a cooperates. The seat 10^b on the valve member is curved or convexed and permits the 110

rocking of the valve on the seat. The valve member has guiding fins or projections 12^a depending therefrom, two of these fins arranged opposite each other being provided 5 with bevelled faces 13^a through which the valve 11^a is caused to turn so as to make it self grinding and to bring new parts of the valve into cooperation with the valve seat 10^a. The valve 11^a has the rod 14 of the 10 lower piston extending therethrough and in order that there will be no leakage about the rod 14 through the valve 11^a the latter carries a packing which, in this instance, is in the form of flanged leather rings 21 secured 15 in place by a locking collar 22 and separated by a spacing ring 23. This packing is flexible and permits a slight lateral or rocking movement of the valve 11^a relatively to the rod should the rod be slightly out of center 20 due to wear in rod guides. This flexible packing with the convex seat 10^b will therefore insure the seating of the valve under all conditions.

Movement of the upper piston or bucket 25 is effected through a hollow piston rod 24 surrounding the piston rod 14 and connected with the bucket or piston 2. This connection, in this instance, is effected by a coupling member 25 to one end of which 30 the piston rod 24 is secured. The other end of the coupling member connects with an externally threaded boss 26 on a cage 27, the latter having a ring 28 at its lower end which is internally threaded and engages 35 external threads on the piston or bucket 2 about the valve 11^a. It will be seen that the hollow piston rod 24 connects with the upper bucket or piston 2 on the exterior of the bucket. This arrangement permits the 40 making of a larger passageway through the bucket 2 and at the same time makes it possible to use only one seat on the bucket for engagement by the valve 11^a. The valve 11^a will move to its seat by the pressure of 45 the water above it, but this seating may be assisted by a helical spring 18^a which at its lower end seats against the valve 11^a and at its upper end seats against the cage about an annular projection 19^a.

50 It is desirable to provide a packing about the piston rod 14 to prevent surge passing into the hollow piston rod 24 and with this end in view the annular projection 19^a is provided with a pocket 29 in which a packing 55 30 is received to fit tightly about the piston rod 14, a locking ring 31 securing the packing in the pocket. This packing is open at all times to the pressure above the valve of the upper piston or bucket.

60 From the foregoing it will be seen that there has been provided a piston or bucket which has a maximum water way both through the body of the piston and about the valve. The possible slip on the lower 65 valve is limited to one metal seat and this

without packing of any kind. The possible slip on the upper valve is limited to one unbroken metal seat and to a packing around a small polished rod carrying the lower piston. Both valves have a tendency to rotate, which makes them self-grinding and brings new parts of the seats in contact at each stroke, this being particularly valuable when the water being pumped contains sand, grit or other foreign substance. The 70 area of the packing in the top piston valve has smaller dimensions than those in pumps carrying the packing on a stem which supports the piston. The load of each piston is carried through a cage which distributes 75 such load more evenly than when the load is placed upon a central stem as now commonly used. The piston rod of the lower valve has a packing about it carried by the 80 cage of the upper piston. This increases the 85 mechanical efficiency of the pump by decreasing the slippage of water from a surge between the two piston rods, this being particularly valuable under heavy loads of pressure and producing a smoother pump operation. Increased passageway through the 90 pistons together with the springs operating on the valves, makes it possible to obtain a higher piston speed, a more rapid and positive closing of the valves, thus obtaining a 95 larger quantity of water from a given sized piston and cylinder and longer life to the pistons without attention.

What I claim as my invention and desire to secure by Letters Patent is: 100

1. A deep well pump comprising a barrel, two buckets arranged in the barrel, one above the other and having sloping seats, two valves, one for each sloping seat of a bucket controlling the flow of liquid 105 through such bucket, two cages, each connected to one of the buckets about the valves, two rods, each connected to one of the cages, the rod of the upper bucket being hollow and having the rod of the lower bucket 110 extending therethrough, said rod of the lower bucket also extending through the valve of the upper bucket, a packing carried by said valve of the upper bucket and cooperating directly with said rod and a guide 115 for the rod of the lower bucket, arranged in the upper bucket below the packed valve.

2. A deep well pump comprising a barrel, two buckets arranged in the barrel, one above the other, two valves, one for each 120 bucket controlling the flow of liquid through a bucket, two cages, each connected to one of the buckets about the valves, two rods, each connected to one of the cages, the rod of the upper bucket being hollow and having the rod of the lower bucket extending therethrough, said rod of the lower bucket also extending through the valve of the upper bucket, a packing carried by said valve of the upper bucket and cooperating 125 130

directly with said rod, and a packing continually exposed to the pressure above the valve of the upper bucket for preventing surge between the rod of the lower bucket 5 and the rod of the upper bucket.

3. A deep well pump comprising a barrel, two buckets operating in the barrel, one above the other, each bucket having a passageway therethrough, two valves, one controlling the flow through each bucket passageway, two cages, each connected to a bucket about the valve thereof, two rods, each connected to one of the cages, the rod of the upper bucket being hollow and having the rod of the lower bucket extending therethrough and the rod of the lower bucket extending through the valve of the upper bucket and through the passageway of such upper bucket, and a guide provided 10 in the passageway of the upper bucket for the rod of the lower bucket.

4. A deep well bucket comprising a barrel, two buckets arranged in the barrel, one above the other, two valves, one for each bucket controlling the flow through such bucket, the upper one of said valves having a spherical portion and the bucket having a conical seat for cooperation with said spherical portion, two rods, each connected 15 to one of the buckets, the rod of the upper

bucket being hollow and having the rod of the lower bucket extending therethrough and also extending through the valve of the upper bucket and a yielding packing between the valve of the upper bucket and the rod of the lower bucket permitting the valve to seat itself notwithstanding the fact that the rod may be slightly out of center. 35

5. A deep well pump comprising a barrel, two buckets operating in the barrel, one above the other, each having a passageway therethrough, two valves, each controlling the flow through the passageway of one of the buckets, two cages each connected to a bucket above the valve thereof, two rods, each connected to one of the cages, the rod of the upper buckets being hollow and having the rod of the lower bucket extending therethrough, and the rod of the lower bucket extending through the valve of the upper bucket and through the passageway of such upper bucket, a guide packing continually exposed to the pressure above the valve of the upper bucket for preventing the surge between the rod of the lower bucket and the rod of the upper bucket, and a guide in the passageway of the upper bucket for the rod of the lower bucket. 40 45 50 55
